UNITED STATES PATENT OFFICE

1,968,257

PORTABLE BENCH SANDER

Harry L. Myers, Toledo, Ohio, assignor to The American Floor Surfacing Machine Company, Toledo, Ohio

Application September 5, 1931, Serial No. 561,478

5 Claims. (Cl. 51—170)

This invention relates to an improved portable machine for abrading and sanding work employed in working, dressing, and finishing wood surfaces, the general characteristics of said machine being such as to permit it to be conveniently entitled Portable bench sander.

In developing the improved machine, I have endeavored to provide a worthy contribution to the trade and art, which may be used to advantage in innumerable manners.

The purpose of the invention is to provide a light-weight belt sander with exceptional speed, abundant electric power, and assured dependability for surfacing and completely conditioning work of all characters in cabinet shops, furniture manufacturing establishments, wood-working mills, and in fact by any one dealing with flat wood surfaces requiring surfacing preparatory to finishing and painting.

Interpreted otherwise, I have evolved and produced a satisfactory light-weight sanding plane which embodies an electric motor operable directly from the light socket or wall plug, easily handled and transported from place to place and highly satisfactory for surfacing and reconditioning table tops, painted boat surfaces, furniture, school desks, and the like.

In addition to the aforesaid commercial advantages, the machine is further qualified as possessing many manufacturing and assembling advantages, such as appreciably contribute to the success and efficiency of the endeavor as a whole.

Referring now to the drawings wherein like characters of reference are employed to designate like parts throughout the same:—

Figure 1 is an elevational view of a complete portable bench sander constructed in accordance with the present invention.

Fig. 2 is a view of the reverse side of the machine represented in Fig. 1 showing the mechanism visible from this side and showing the dust collecting bag removed.

Fig. 3 is a top plan view of Fig. 1, with the bag removed.

Fig. 4 is an end elevation of Fig. 1 observing the same in a direction from left to right.

Fig. 5 is a side view of a removable handle equipped unit.

Fig. 6 is a fragmentary sectional view illustrating said unit and the associated dust fan assembly.

Fig. 7 is a transverse vertical section through the lower portion of the frame or chassis.

Fig. 8 is a sectional view on the line 8—8 of Fig. 1.

Fig. 9 is an enlarged detail section of the adjustable idler pulley.

Fig. 10 is a horizontal sectional and elevational view illustrating the mechanical relationship of the idler pulley to the frame and the spring-pressed tensioning and thrust device.

Fig. 11 is a fragmentary sectional and elevational view on a horizontal plane through a portion of said thrust connection.

Fig. 12 is an elevational view of a special pendulous-like fixture.

Fig. 13 is a top plan view of the fixture represented in Fig. 12.

Fig. 14 is a perspective view of a retaining leaf spring.

One of the major parts of the improved machine is generally distinguished and denoted by the numeral 15, and this may be referred to alternatively as the frame or chassis. This frame comprises, as seen in Fig. 2, a substantially horizontal top plate 16 having a downturned rear end portion 17, this being joined to a horizontal bottom plate 18 (see Fig. 7) by way of a perpendicular side plate 19. The plates 18 and 19 are reinforced and further secured together by way of longitudinally spaced transversely extending connective webs 20 and 21, these being of general triangular form as illustrated in Fig. 7. The web 20 is provided with an apertured boss 22, while the edge of the web 21 is provided with a clearance notch 23. Joined to the bottom plate 18 through the medium of spacing abutments 24 is a backing plate 25 to which the facing or platen 26 is separably connected. The casing including this frame is provided at the front end portion with an attaching ear 27 which serves a purpose to be hereinafter described.

Secured to the top plate near this ear is an appropriate handle or hand grip 28. The numeral 29 designates the horizontally disposed longitudinally extending motor, the electrical portion of which is of ordinary construction. The shell, or casing of the motor is of special configuration at the rear end portion thereof. As shown for example in Fig. 2, the section 30 is molded to embody a vertically elongated gear housing 31 having a terminal attaching flange 32. On one side of this housing is a cover plate 33 (see Fig. 8) and on the opposite side is a three-part extension.

One part, indicated by the numeral 34 is fashioned to accommodate end thrust bearings 35 and 36 which serve to support the power take-off shaft 37. The inner end of this shaft is provided with a worm gear 38 in mesh with a worm drive 39 on the motor shaft 40. The second part of

the extension comprises a downwardly and rearwardly inclined receptacle 41 constituting the body portion of the sprocket drive enclosure. This enclosure is provided with a removable cover 5 plate 42 and serves to accommodate the upper sprocket wheel 43 as well as the lower companion sprocket wheel 44. A sprocket chain, not shown, is trained over these sprockets as is obvious to transmit the motive power from the shaft 40 to 10 the driven shaft 45 through the medium of the power take-off shaft 31 and the sprocket drive. Alined with, and extending from the sprocket 44 is a tubular bearing 46 provided with end thrust bearings 47 and 48 to accommodate the shaft 45. 15 The rubber-covered drive pulley 49 is keyed on this shaft 45, and underlies the adjacent end portion 17 of the frame.

I desire now to call attention to the numeral 50 which generally designates the especially fashioned casting constituting an important part of the dust-collector means. In fact, this unit includes a cup 51 fastened to the flange 32 to form a housing for the fan 53, (see Fig. 6). The rim of the cup is provided with a peripheral discharge 20 neck 54 with which the bag 55 (see Fig. 1) is connected. The dust conveying and intake spout is represented by the numeral 56. It is of appropriate configuration, connected concentrically to the cup 51 and has an appropriately designed 25 inlet nozzle 57.

Formed integral with this dust intake nozzle is a rearwardly and downwardly inclined hand grip 58 including a horizontal brace 59. This assembly of details distinguishes the casting 50 30 as original, and unique, the arrangement being particularly advantageous from a standpoint of simplification of manufacture and assembly.

The aforesaid positively driven pulley 49 serves to accommodate an endless abrasive belt 60, said 40 belt being trained, at its front end, over an idler pulley 61. This pulley 61 is preferably of the special construction and arrangement depicted in Fig. 9. As represented in the last-named figure, the idler pulley (sometimes referred to broadly as a rotary guide) is cast to provide for self-lubrication features. The relatively thick end 62 is recessed to accommodate the end thrust bearing 63 and a packed retaining screw cap 64. The cap 64 is provided with a bushing 65, which takes 45 care of the shaft 66, said shaft 66 being journaled in a bearing 67 on the front end of the adjustable carrier arm 68.

At the opposite end of the pulley is an inwardly spaced diaphragm 69 formed with an oil cup 70 having a removable filler plug 71. Fitted in the diaphragm and cup is a bearing 72. These parts serve to define an oil chamber 73 for effective 50 lubrication results.

The pulley 61 and carrier arm 68 together with 60 associated parts, constitutes a unitary assembly, associated with a special belt tensioning and pulley mounting structure. An important part of this structure comprises a fixture generally distinguished by the numeral 74. As seen in Figs. 65 10 to 13 inclusive, this fixture embodies a cylindrical stem 75 having a U-shaped clip 76 at one end pivotally connected with shank 77 of the headed end of a slidible plunger rod 78.

The cotter key equipped end of this rod 78 70 extends loosely through the aforesaid boss 22. Surrounding the rod is an expansion coiled spring 79 bearing at one end against a retention washer 81, and at its opposite end against the headed end of the rod. At its outer end, this 75 stem 75 is formed with a fork whose arms are

represented by the numerals 82 and 83 respectively. Rising from the front end of the arm 82 is a standard 84 carrying an elongated eye 85 at its upper end. This eye is mounted for oscillation on a bolt 86 supported in the ear or lug 27. 80 This same bolt 86 passes through a retaining ring 87 forming an integral part of a spring retention clip. This clip includes a flat spring 88 which bridges the joint between the parts 27 and 85 and is cooperable with a keeper finger 89 carried by the eye 85. The arm 68 is swingably mounted on a spindle bolt 90 located between the arms 82 and 83 and associated with the apertured free end portion of said arm is an adjusting screw 91 threaded into a socket 92 in the stem 75 as seen 90 in Fig. 11.

The numeral 93 designates a thrust spring interposed between the arm 68 and the end of the stem 75. The fixture 74 has a pendulous action and is designed to allow the idler pulley 61 to be moved toward and from the frame to shorten the 95 distance between the pulley and the main drive pulley to facilitate exchange of abrasive belts.

The inward swinging action of the fixture 74 together with the idler pulley 61 is resisted by 100 the spring-pressed plunger arrangement depicted in Fig. 10. This is evident because of the fact that the plunger rod is pivotally and directly connected with the fixture 74 through the medium of the laterally directed stem portion 75. Otherwise stated, the expansion of the spring 79 exerts a resilient end thrust action on the swingable fixture 74 to force the idler 61 into yieldable frictional contact with the interior of the endless belt. Because of this spring tension belt exchange feature, it is essential to have means to maintain the idler pulley in a temporarily tripped state to relieve the endless belt of tension so as to facilitate the exchange. In fact, it is evident that when pressure is brought to bear against 115 the idler 61 it swings in a direction toward the frame and in so doing the keeper lug 89, which is previously beneath the flat spring 88 as seen in Fig. 1, snaps in front of the adjacent edge of the spring leaf during which time the parts are temporarily relieved of spring stress to expedite belt exchanging.

In addition to having this pendulous or swing action, the arm 68 and set screw 91 provides an independent adjustment allowing the idler to 120 be canted to avoid accidental displacement of the belt.

The idea of providing a centralized longitudinally reciprocated spring-pressed plunger structure on the frame, together with the swingable 130 bracket or fixture 74, and the novel independent adjustable mounting and the idler on said fixture, is of primary importance and regarded as a feature of far-seeing novelty.

The spring 88, keeper 89, and associated details 135 may be referred to as a quick-acting latch arrangement for holding said bracket 74 in a position which makes it convenient and easy to replace belts.

I also wish to emphasize the novel lubricating 140 feature of the idler pulley as detailed in Fig. 9, as well as the peculiarity in casting the rear end portion of the motor shell, together with the equally peculiarly shaped unit 50 forming the major portion of the dust collector and fan 145 arrangement.

It is thought from the foregoing description that the advantages and novel features of the invention will be readily apparent.

It is to be understood that changes may be 150

made in the construction and in the combination and arrangement of the several parts, provided that such changes fall within the scope of the appended claims.

5 Having thus described my invention, what I claim as new is:—

1. A machine of the class described comprising a frame, a drive pulley on said frame, means for operating said pulley, a carrier fixture swingably mounted on the frame for forward and rearward pendulous action, a bearing carried by said fixture, an idler pulley including a shaft journaled for rotation in said bearing, and spring-pressed thrust means on said frame operatively connected 10 with said fixture, together with resilient latch means for holding the fixture in a predetermined retracted state to facilitate application and removal of abrasive belts.

2. In a structure of the class described, a frame, 20 a spring pressed rod slidably mounted on said frame, a hanger bolt carried by a stationary lug on said frame, a fixture embodying an eye mounted for oscillation on said bolt and further including a forked portion operatively connected with 25 the adjacent end of said spring-pressed rod, an idler pulley, a bearing equipped arm operatively connected with said pulley, swingably connected with the forked portion of said fixture, adjusting means between the arm and fixture, a keeper lug 30 carried by said eye, and a spring latch clip carried by said stationary lug, said keeper lug being co-operable with said spring latch clip to maintain the fixture in a predetermined retracted state to resist the tension of the spring-pressed rod.

3. In a machine of the class described, in combination, a frame including a plurality of walls formed with integral longitudinally spaced transversely disposed webs, one web being apertured and the other web being formed with a clearance 40 notch, a rotatably mounted propulsion drum on said frame, a motor on the frame, an operating connection between the motor and drum, an idler pulley having a projecting journal at one end, an arm formed with a bearing in which said journal 45 is rotatable, a hanger fixture embodying a vertical standard having a rocker eye at its top formed with a keeper, a fork formed at the bottom of said standard provided with arms between which said first-named arm is pivotally mounted, 50 a horizontally disposed cylindrical stem extending at right angles from said fork into said frame, an adjustable connection between said arm and stem, a rod slidable through the aperture in said web and notch in the remaining web, an expansion coiled spring surrounding said rod to exert a 55 longitudinal yieldable thrust on the rod, and a

pivotal operating connection between said rod and stem, together with a bolt carried by the frame on which said eye is rockably mounted, and a spring carried by said bolt with which said keeper is releasably engageable.

4. A machine of the class described comprising a frame, longitudinally spaced front and rear belt guides disposed transversely of said frame, the front guide being in the form of an idler pulley, an endless belt trained over said guides, a horizontally disposed hanger bolt fixedly mounted on the frame adjacent said idler pulley and projecting outwardly beyond the adjacent longitudinal edge of the frame, a carrier fixture mounted for oscillation on said bolt and having forward and rearward pendulous action outwardly of said frame, relatively stationary resilient latch means co-operable with said fixture to temporarily hold the latter in a retracted position to facilitate exchange of belts, means for pivotally and adjustably connecting one end portion of the idler pulley to said carrier, and a self-compensating spring-pressed belt tensioning and thrust means mounted on the frame and operatively connected with said carrier fixture.

5. A machine of the class described comprising a frame, a stationary lug attached to and rising from the frontal portion of said frame, a hanger bolt carried by said lug and projecting outwardly in a horizontal plane beyond the adjacent edge portion of the frame, a guide pulley carrier fixture having its major portion disposed outwardly beyond the adjacent edge portion of the frame to provide the desired forward and rearward pendulous motion for said fixture, said fixture being mounted for swinging on a horizontal axis on the hanger bolt, a resilient latch clip carried by said lug, said fixture being provided with a keeper lug engageable with said clip, automatically operable spring-pressed thrust means mounted on said frame, an operating connection between the thrust means and the carrier fixture, a bearing arm mounted on a vertical axis on the carrier fixture, adjusting means for said bearing arm, an idler pulley provided at one end with a journal mounted for rotation in the bearing of said arm, said idler pulley being disposed beneath the adjacent frontal portion of the frame and extending transversely of the frame, a transversely disposed longitudinally spaced motion transmitting pulley on the rear portion of the frame, an endless belt trained over said pulleys, and operating means for the motion transmitting pulley also mounted on the frame.
